UNITED STATES PATENT OFFICE.

FRED H. GEORGE, OF LISBON, OHIO.

HAT AND COAT RACK.

No. 839,749.

Specification of Letters Patent.

Patented Dec. 25, 1906.

Application filed July 16, 1906. Serial No. 326,451.

To all whom it may concern:

Be it known that I, FRED H. GEORGE, a citizen of the United States of America, residing at Lisbon, in the county of Columbiana and State of Ohio, have invented certain new and useful Improvements in Hat and Coat Racks, of which the following is a specification, reference being had therein to the accompanying drawings:

- 10 This invention relates to coat and hat racks; and the invention relates more particularly to a guard for preventing wearing-apparel from being stolen or accidentally misplaced.
- 15 To this end I have devised a simple and inexpensive guard which can be easily placed upon a wall to shield and guard an umbrella, hat, and coat.

The guard comprises a woven-wire cage 20 containing hooks from which articles can be suspended. The cage is hinged to a wall and is locked in engagement therewith by a lock of a conventional form.

The detail construction of my improved 25 guard will be presently described, illustrated, and specifically pointed out in the appended claims.

Referring now to the drawings forming part of this specification, Figure 1 is a perspective view of my improved guard; and Fig. 2 is a similar view, the cover or woven fabric of the guard being removed.

To put my invention into practice, I construct my guard of a substantially rectangular metallic frame 1, having its lower rail 2 bent outwardly to form a clearance 3, the object of which will presently appear. The top rail 4 and the bottom rail 2 are connected together by a curved metallic band 5, which is 35 further braced by strap 6, arranged transversely of the frame 1, said strap being bent substantially the same shape as the lower rail 2 of the frame.

The frame 1, band 5, and strap 6 are 40 closed by a woven-wire fabric or netting 7, which is suitably secured to the frame 1, and is adapted to protect articles carried by the frame. To support articles within the frame, I provide the band 5 with a hat-hook 45 8 and a coat-hook 9, the latter carrying an ordinary coat-form 10. The strap 6 is provided with a resilient clasp 11 of a conventional form for supporting an umbrella within the frame 1.

My improved guard is preferably mounted 55 upon a wall by hinges 12 and is locked in engagement with the wall by bending the side rail 12^a of the frame 1 to form a hasp 14, adapted to engage over a staple 15, driven or otherwise secured in the wall. An ordinary 60 lock 16 can be used to secure the hasp 14 upon the staple 15.

A person desiring to use my improved guard is provided with a key to open and close the guard, and should a coat or umbrella be of greater length than the guard the clearance 3 permits of the articles extending below the guard. In order that the guards can be properly identified, they can be provided with suitable numbers, characters, or name-plates (not shown) or may be otherwise labeled upon the wall near each guard.

It will be apparent from the foregoing that I have devised a useful and easily-manipulated guard for wearing-apparel which is applicable to large cloak-rooms, check-rooms, cafés, and similar places where wraps are temporarily disposed of.

What I claim, and desire to secure by Letters Patent, is—

1. In a hat and coat guard, the combination with a suitable support, of a frame hinged to said support and having a clearance at its lower edge, a band carried by said frame, a strap arranged transversely of said frame, a clasp secured to said strap, hooks carried by said band, a coat-form carried by one of said hooks, a wire-netting arranged over said frame, and means to lock said frame to said support, substantially as described.

2. In a hat and coat guard, the combination with a suitable support, of a frame hinged to said support and having a clearance at its lower edge, an umbrella-clasp supported by said frame, hat and coat hooks supported by said frame, a wire-netting arranged over said frame, and means to lock said frame to said support, substantially as described.

In testimony whereof I affix my signature in the presence of two witnesses.

FRED H. GEORGE.
